HIS ATTORNEY

UNITED STATES PATENT OFFICE.

ORANGE O. OZIAS, OF DAYTON, OHIO, ASSIGNOR TO THE COMPUTING SCALE COMPANY, OF OHIO.

DESIGN FOR A PLATFORM FOR SCALES.

SPECIFICATION forming part of Design No. 31,926, dated December 5, 1899.

Application filed October 30, 1899. Serial No. 735,330. Term of patent 7 years.

To all whom it may concern:

Be it known that I, ORANGE O. OZIAS, a citizen of the United States, residing in Dayton, in the county of Montgomery and State of Ohio, have produced a new and original Design for a Platform for Scales, of which the following is a specification, reference being had to the accompanying drawings, forming part thereof, in which like numerals refer to like parts.

In the drawings, Figure 1 represents an elevation view of a platform for a scale embodying my invention and design, and Fig. 2 is a side elevation view thereof.

The leading or essential feature of my design consists of a circular plate having four projections from one face thereof and near the periphery of said platform, said projections being at the corners of an imaginary rectangle and some of said projections being of different lengths.

In said drawings, 10 represents said circular platform, and 11 represents said projections from one face of said platform 10 and near the periphery thereof, said projections 11 being at the corners of an imaginary rectangle and some of said projections 11 being of different heights, as shown in Fig. 2, the upper edge of said platform 10 being beveled, substantially as shown in Fig. 2.

What I claim is—

The design for a platform for a scale, as shown and described.

In witness whereof I have hereunto set my hand this 30th day of September, 1899.

ORANGE O. OZIAS.

Witnesses:

CHARLES W. JAMES,
IRA C. KOEHNE.
